UNITED STATES PATENT OFFICE.

ALFRED G. HEGGEM, OF TULSA, OKLAHOMA.

UNDERREAMER.

Application filed January 16, 1922. Serial No. 529,650.

My invention relates to underreamers for drilling wells, and while in certain aspects it is especially directed to the production of a strong, reliable and efficient tool employing a single large and rugged bit capable of drilling straight ahead and coincidently performing an underreaming operation, there are other aspects of the invention which may be advantageously applied to 5 the well known type of underreamers having a pair of expanding bits or cutters, examples of this latter type of underreamers being disclosed in Patents No. 748,054, granted to Edward Double December 29, 10 1903, and No. 827,595, granted to Elihu C. Wilson July 31, 1906.

The principal object of the invention is to provide an underreamer in which the cutting means thereof may automatically assume drilling position when the tool issues through the bottom of a well casing and in which, upon the underreamer passing out of the top of the casing, the cutting means will automatically remain in a position enabling 20 the underreamer to pass through the casing, thereby not only permitting the tool to be again lowered in the casing without adjustment but relieving the mechanism of the violent stress to which it would be subjected 25 as a result of the unrestricted expansion of the cutting means to drilling position when the underreamer passes out of the top of the casing; and also enabling a new bit to be substituted with a minimum expenditure 30 of labor.

Another object of the invention is to provide means for actuating an underreamer bit so as to cause the portions thereof normally projecting beyond the periphery of 40 the stock to be withdrawn within the lines of the stock, thus enabling the tool to pass through the casing of the well; and a further object of the invention is to produce an underreamer having a bit formed with a cutting portion on its lower side in alignment 45 with the stock as well as cutting portions adapted to perform the function of underreaming.

The primary feature of the invention, generally stated, consists in constructing the underreamer with a stock and with cutting means movably mounted thereon, said cutting means being adapted when in drilling position to project outwardly beyond the 50 periphery of said stock and also being adapted to assume an inoperative position per-

mitting the underreamer to pass through the casing of a well, and in movably mounting on said stock automatically operating means for retaining said cutting means in inoperative position upon the withdrawal of the underreamer from the well casing, said last named means being adapted upon lowering the underreamer into the casing to be brought to a position permitting said cutting means to assume the drilling position upon the issuance of the underreamer through the bottom of the casing.

Another feature of the invention consists in providing the underreamer with a stock, 70 a spring, cutting means having cutting portions adapted when in drilling position to project outwardly beyond the periphery of said stock and also adapted to assume an inoperative position permitting the tool to pass 75 through the casing of a well, and with means operatively connecting said cutting means to said stock through said spring, and in providing means for relieving said cutting means of the pressure of said spring during the movement of said cutting means to an inoperative position allowing the underreamer to pass through the well casing.

Still another feature of the invention consists in forming the bit of an underreamer 85 with a cutting portion on its lower side and with a bearing face on its upper side to engage an underreamer stock, and in also providing the bit at its opposite ends with cutting portions extending at an angle to the 90 cutting portion first mentioned and adapted to project outwardly beyond the periphery of the underreamer stock.

There are other features of the invention relating to particular details of construction and special combinations of the elements of the mechanism, all as will herein-after appear.

In the drawings illustrating the invention, the scope whereof is pointed out in the 100 claims,—

Figure 1 is an elevation of an underreamer embodying the invention, the parts being shown in drilling position and the lower portion of the well casing through 105 which the device operates being shown in section.

Figure 2 is a detail vertical sectional view of the underreamer shown in Fig. 1, the cutting means being in the inoperative position 110 enabling the tool to pass through the well casing, portions of the device being broken

away and the upper end of the well casing being indicated by dotted lines.

Figure 3 is a detail vertical sectional view similar to Fig. 2, but illustrating the positions assumed by the parts in drilling.

Figure 4 is a detail elevation of the underreamer showing the parts in drilling position, the upper portion of the device being broken away and the view being taken at 10 right angles to that shown in Fig. 1.

Figure 5 is a detail longitudinal section of a portion of the stock of the underreamer.

Figure 6 is a section on the line 6—6, Fig. 3.

15 Figure 7 is a section on the line 7—7, Fig. 3.

Figure 8 is a section on the line 8—8, Fig. 3.

20 Figure 9 is a detail vertical section of the lower end of the underreamer, the parts being in drilling position.

25 Figure 10 is a detail sectional view of the lower end of a modified form of underreamer embodying certain features of my invention, the cutting means being shown in drilling position.

30 Figure 11 is a view corresponding to Fig. 10 but illustrating the positions assumed by the parts when the underreamer is withdrawn from the well casing.

35 Figure 12 is a view, partly in section and partly in elevation, of the lower end of a modified form of underreamer embodying certain features of the invention, the device being in drilling position.

Figure 13 is a view corresponding to Fig. 12, but illustrating the position assumed by the parts when the tool is withdrawn from the well casing.

40 Figure 14 is a sectional view on the line 14—14, Fig. 12.

Figure 15 is a sectional view on the line 15—15, Fig. 13.

45 The stock 1 of the underreamer is preferably provided at its upper end with a threaded tapered pin 2 forming means for connecting the underreamer to the devices with which it is associated in drilling. Below the tapered pin the stock may conveniently be provided with the usual wrench seats 3.

50 The stock is formed with a downwardly opening longitudinally extending chamber or recess 4 adapted to receive a spring 5 and cooperating rod 6 through which the bit 7 is yieldingly connected to the stock. The lower end of the rod 6 is movably connected to the central portion of the cutting means 7, preferably by forming said rod with an eye for receiving a pivot pin 8 which extends 55 into suitable pivot openings 9 with which the cutting means or bit is provided. At its upper end the said rod may be threaded to receive a nut 10 which holds in place a washer 11 bearing upon the upper end of the spring 5. Intermediate of its length

the rod is slotted to receive a transversely extending key 12 whose ends project into longitudinally extending slots 13 opening through opposite sides of the stock 1 and communicating with the chamber 4 within which the rod 6 operates. Where the turning movement of the bit 7 is effected without any accompanying lateral movement of the rod with respect to the stock, said rod may be enlarged adjacent the key 12, as indicated at 14, thus not only reinforcing the rod adjacent the slot therein, but also preventing intrusion of mud. Above the enlargement 14 the rod 6 passes through a collar 15 which may be secured within the recess 4 of the stock by means of pins 16 to constitute a seat for the lower end of the spring 5.

Operatively connected to the ends of the key 12 are slides 17 which are adapted to move longitudinally of the stock 1 in slots 18 or recesses formed therein and communicating with the respective slots 13. These slides may be advantageously connected to the key 12 by means of pins 18, the outer ends of said key being received in slots or key recesses 19 formed in the slides and the ends of said key being preferably of somewhat reduced dimensions to afford shoulders limiting the inward movement of the slides. For the purpose of introducing the pins 18 in the assembling of the mechanism the stock is preferably provided at its periphery somewhat below the position occupied by said pins during drilling with a plurality of oppositely disposed depressions 20, permitting the pins 18 to be put in place when the key 12 and slide 17 are drawn downwardly a short distance.

If desired, the recesses of the stock in which the slides 17 operate may be somewhat wider at the periphery of said stock than inwardly thereof and may conveniently be formed with outwardly flaring side walls 21 forming beveled guides against which the correspondingly beveled sides of the slides 17 bear. The portions 22 of the slide receiving recesses adjacent the transverse slots 13 of the stock are made sufficiently deep to receive the thickened portions 23 with which the slides 17 are preferably formed adjacent the ends of the transverse key 12, and also to permit the blocks 24 mounted on said slides to be forced inwardly toward the center of the stock by the well casing. By the engagement of the portions 23 of the slides with the stop shoulders 25 of the stock the downward or spring compressing movement of the rod 6 is limited to an amount ensuring at all times the proper operative relation of the means by which the turning or rotation of the bit 7 with respect to said rod and the underreamer stock is effected.

The slides 17 are furnished with lugs or projections adapted to extend outwardly be-

yond the periphery of the stock 1 so as to be capable of contacting the lower end of the well casing 26 and are also adapted to move inwardly toward the axis of said stock so as to pass through the casing. Instead of rigidly connecting these lugs or projections to the slides 17, which would necessitate an inward movement of the slides to permit the underreamer to pass through the casing, said projections are preferably formed as blocks 24 which are movably mounted on the respective slides with capability of moving in and out transversely of the stock 1. The outer faces 27 of the blocks may be rounded to conform to the curvature of the exterior of the stock 1, and the outer portions of their upper ends are preferably beveled or inclined as at 28 for the purpose of causing said blocks to be forced inwardly toward the axis of the stock when the blocks are forced against the ends of the well casing in the operation of withdrawing the underreamer from the well. In order that the blocks 24 may be reversible their lower sides may be similarly provided with beveled faces 28. To limit their outward radial movement the blocks 24 are preferably provided with oppositely disposed longitudinally extending flanges 29 which are overlapped by corresponding portions 30 of the respective slides 17; and to compel the expansion of said blocks when they have passed out of the lower end of the casing 26 the stock 1 is formed with inclined or beveled shoulders 31 with which the upper ends of the blocks are respectively adapted to engage. When by reason of the expansion of the spring 5 the slides 17 are caused to move upwardly on the stock 1, the blocks 24 will cooperate with the inclines 31 and thereby be forced outwardly to their full extent.

The underreamer is provided with means movably mounted on the stock 1 for retaining the cutting means or bit 7 in a position permitting the underreamer to pass through the well casing, the said retaining means being automatically operable to maintain the cutting means in said position upon the withdrawal of the tool from the well. The retaining means preferably employed consist of a plurality of oppositely disposed spring pressed latches 32 pivotally mounted upon the stock 1 by means of pins 33. The latches operate in recesses 34 of the stock which extend above and communicate with the recesses for the slides 17, the said recesses 34 being of a depth sufficient to enable said latches to assume a position permitting them to pass through the casing 26. Springs 35, which are operatively interposed between the respective latches and the stock 1 and which are preferably of leaf form, constantly tend to move said latches outwardly beyond the periphery of the stock, as illustrated in Fig. 2. When thus expanded the latches 32 will engage the upper end of the casing 26 when the underreamer is lowered into the well, such engagement of the latches with the casing resulting, during the lowering of the underreamer, in forcing the said latches inwardly against the pressure of the leaf springs 35 until the latches are enabled to enter the casing. To effect this inward camming of the latches in an efficient manner each of them may advantageously be formed on its outer side with a sloping or beveled shoulder 36 for contacting with the upper end of the well casing.

The portions 37 of the latches extending below the sloping shoulders 36 are of reduced cross section so that they may freely enter the well casing 26 before the latches 32 are moved inwardly when the underreamer is lowered into the well and also in order that said latches may move outwardly and assume the position shown in Fig. 2 before they pass entirely above the upper end of the casing. When in an expanded position the lower ends of the latches overlie the upper ends of the respective slides 17, thereby preventing an upward movement of the latter with respect to the stock 1 and thus checking the expansion of the spring 5 which would result in causing the cutting means or bit 7 to be rotated to its normal or drilling position. To limit the outward movement of the latches when the underreamer is withdrawn from the well their lower ends may be provided with lugs 38 adapted to overlap the neighboring inner faces of the slides 17. When, as shown in Fig. 3, the parts of the underreamer are in drilling position the lower ends 37 of the latches stand behind the upper ends of the slide 17 and the latches thus are prevented from moving outwardly.

The cutting means 7 which is yieldingly mounted upon the stock 1 through the instrumentality of the rod 6 to which it is movably connected, is adapted when in drilling position to project outwardly beyond the periphery of the stock 1 and beyond the well casing, and is also adapted to assume an inoperative position enabling it to pass through the casing. The cutting means employed preferably is constructed as an integral bit 7 having oppositely disposed cutting portions 39 adapted, when in drilling position, to project outwardly beyond the periphery of the stock, and also having a cutting portion 40 located between said cutting portions 39 and extending radially of said stock. Instead of extending diametrically across the bit in a single transverse plane, the cutting edge of the portion 40 may, if desired, be formed as a plurality of cutting edges 41 which slope upwardly from the middle of the bit toward the outer

cutting portions 39. As shown in Figs. 1, 3 and 4, the ends 42 of the bit 7 may be and preferably are conically curved, being tapered upwardly toward the lower end of the stock. The bit is slotted upon its upper side to form upwardly projecting webs 43 between which the lower end of the rod 6 extends and operates; and these webs are provided with alined perforations for receiving the pivot pin 8 by which the bit 7 is attached to said rod. At one end of the bit the webs 43 slope downwardly and are preferably somewhat beveled, as indicated at 44, in order that the bit may, without excessive turning, assume a position enabling it to pass through the well casing. This reduces the extent to which the bit is required to be slotted for the operation of the rod 6 and consequently preserves the strength of the bit.

The lower end of the stock 1 conforms in shape to the upper end of the bit 7, thus affording bearing faces 45, 46, 47, 48, 49 and 50 which, when the bit is in drilling position, respectively form seats or bearings for the bearing faces or surfaces 51, 44, 52, 53, 54 and 55 of the bit. Ample bearing area for supporting the bit during drilling operations is thus provided.

In order to cause it to rotate when the rod 6 effects a compression of the spring 5, the bit 7 is preferably formed on opposite sides with angular slots or guideways 56 which respectively receive inwardly extending pins or trunnions 57 with which the stock is provided at its lower end. The slots 56 are preferably open ended so as to provide for the clearance of any material which may find lodgment therein during drilling.

The underreamer may be assembled as follows: The latches 32 carrying the leaf springs 35 are secured to the stock 1 by their pivot pins 33. The spring rod 6, spring 5 and the spring supporting plug 15 will then be assembled outside of the stock 1 and inserted in the chamber 4 of the stock. The pin 16 will then be inserted to retain the spring seat 15 in place. When these parts have been put in position the blocks 24 are assembled with their respective slides 17 and one of said slides is secured to the transverse key 12 by the pins 18. The free end of the key 12 is then passed through the slot in the spring rod 6 and the other slide 17 with the block 24 mounted thereon is slid onto the key. The spring rod 6 is then drawn down a short distance until the depressions 20 in the stock are opposite the pin openings in the key slots 12, and the remaining connecting pins 18 are inserted. With the rod 6 drawn downwardly the pins or trunnions 55 of the stock are entered in the guide slots 54 of the bit and the latter is attached to the lower end of said rod by the pivot pin 8.

The operation of the mechanism heretofore described will be as follows: Assuming the parts to be in drilling position, as shown in Figs. 1, 3 and 4, the act of withdrawing the tool from the well will cause the blocks or slips 24 to engage the casing shoe at the lower end of the well casing 26. The upward movement of the blocks being arrested, while the upward movement of the stock 1 continues, causes a relative downward movement of the said blocks until their upper ends pass below the shoulders 31 of the stock, whereupon the said blocks 24 will move inwardly toward the axis of the stock and in such position will enter the well casing. This relative downward movement of the blocks 24 produces a corresponding downward movement of the slide 17, the transverse key 12 and the spring rod 6, thus energizing the spring 5 and also allowing the bit 7 to move downwardly with respect to the stock 1. During this downward movement the bit 7 is relieved of the pressure of the spring 5 and the travel of the trunnions 57 in the slots 56 of the bit causes said bit to turn upon the pivot pin 8 and assume an inoperative position (see Fig. 2) enabling the entire underreamer to be drawn into the casing 26. The relief of the spring pressure from the bit enables the latter to turn easily upon the pivot pin 8 without pressure upon the bearing faces at the lower end of the stock.

During the upward movement of the underreamer through the well casing the latter prevents the slips or blocks 24 from expanding radially of the stock and the slides 17 are consequently retained in a position corresponding to the inoperative position of the bit 7. During this upward movement also the latches 32 are maintained in inward position by engaging the interior of the well casing 26. As soon, however, as the shoulders 36 of the latches pass above the upper end of the casing 26 (see Fig. 2) these latches expand beyond the periphery of the stock 1 and their lower ends move outwardly and stand over the upper ends of the respectively adjacent slides 17. In this position the latches 32 prevent the slides 17 from rising on the stock, and it thus results that the spring 5 is prevented from expanding to draw the rod 6 upwardly and pull the bit 7 to drilling position. When the underreamer is wholly withdrawn from the well the bit 7 therefore does not return to drilling position but remains in the inoperative position in complete readiness for reintroduction into the well casing. As has already been pointed out, the retention of the bit in this position is likewise advantageous in that it relieves the mechanism from the great strain due to the sudden pulling of the bit to drilling position and also because it enables a new bit to be substituted with great facility.

Upon again lowering the underreamer into the well casing 26 the upper end of said casing engages the inclined shoulders 36 of the latches 32 and causes the latter to rotate inwardly and be forced within the lines of the periphery of the stock, thus displacing the lower ends of said latches from above the slides 17 and thereby releasing said slides. As the slips or blocks 24 have already entered the well casing before the slides 17 are released from the latches 32, and as the well casing prevents said blocks from expanding, the slides 17 are prevented from moving upwardly with respect to the stock 1 until the said blocks pass below the casing shoe at the lower end of the casing 26. The spring 5 thus remains compressed during the downward passage of the tool through the casing and there is no tendency of the bit 7 to reassume drilling position.

As soon as the blocks 24 pass below the casing shoe at the bottom of the casing they expand outwardly, thus allowing the stock 1 to continue its downward movement while the spring 5, acting through the rod 6, transverse key 12 and slides 17, presses the said blocks upwardly against the casing shoe. The relative movement of the stock and the spring rod and slides thus induced causes the bit to move upwardly with respect to the stock and to assume its drilling position and also results in causing the upper ends of the slides 17 to overlap the lower portions 37 of the latches 32, thus retaining said latches in unlocked position (see Fig. 3).

Figs. 10 and 11 illustrate an application of the invention to the well known form of underreamer disclosed in the Double Patent No. 748,054, heretofore mentioned. In this form of underreamer a plurality of relatively movable bits 58 constitute the cutting means, the said bits being movably mounted upon a transverse key 59 which is carried by a spring rod 60 adapted to effect compression of a spring 61 that is housed within the stock 62 of the underreamer. Mounted upon the stock in suitable recesses on opposite sides thereof are a plurality of latches 63 pivotally connected to said stock by pivot pins 64. Operatively interposed between the underreamer stock and the respective latches are leaf springs 65 which constantly tend to cause said latches to project outwardly beyond the periphery of the stock. When, as shown in Fig. 11, the bits 58 are in the inoperative position permitting the underreamer to pass through the casing, the shoulders 66 of the latches, which are preferably beveled, move outwardly beyond the periphery of said stock as soon as the underreamer is withdrawn from the well far enough to allow said shoulders to emerge from the upper end of the well casing. In this position of the latches their lower ends 67 stand

58, thus preventing the spring 61 from expanding and thereby retaining the bits 58 in their inoperative position in readiness to reenter the well casing. When the bits 58 are in drilling position (see Fig. 10) their upper ends overlap the lower ends 67 of the latches and prevent the latter from projecting outwardly beyond the periphery of the stock 62.

In the operation of withdrawing the underreamer from the well the shoulders 68 of the bits engage the lower end of the casing shoe, thus arresting the bits while the upward movement of the stock 62 continues. This results in a relative downward movement of the bits allowing them to tilt inwardly so as to pass through the casing. As soon as the shoulders 66 of the latches 63 emerge from the upper end of the casing the springs 65 force the latches outwardly and bring their lower ends into locking relation with the bits, thus retaining the latter in collapsed or inoperative position. When the underreamer is again lowered into the well the shoulders 66 of the latches encounter the upper end of the casing and the latches are forced inward so that their lower ends 67 are displaced from above the upper ends of the bits. As soon, therefore, as the bits emerge from the lower end of the casing the spring 61 is enabled to expand and thus draw said bits to drilling position.

In Figs. 12, 13, 14 and 15 my invention is shown as embodied in an underreamer of the character disclosed in the Wilson Patent No. 827,595, already mentioned. In this modified form of my invention 69 is the underreamer stock and 70 is the yieldingly supported rod by which the collapsible cutting bits 71 are movably connected to the stock. These parts may be substantially like those disclosed in the patent last referred to. Mounted in suitable recesses in the stock and pivotally connected thereto by pivot pins 72 are a plurality of latches 73 adapted to be forced outwardly by leaf springs 74 so as to project beyond the periphery of the stock. On account of the small amount of space available for the latches in this form of underreamer it is preferred not to locate them in diametrical alinement but to dispose them in an offset relation as shown in Figs. 14 and 15. The form, function and mode of operation of the latches 73 are as heretofore described 120 with respect to the latches 63.

I claim:

1. An underreamer having a stock, cutting means movably mounted on said stock and adapted when in drilling position to project outwardly beyond the periphery of said stock and also adapted to assume an inoperative position enabling said underreamer to pass through the casing of a well, and means movably mounted on said stock

operating automatically to retain said cutting means in inoperative position upon the withdrawal of the underreamer from the casing.

5. 2. An underreamer having a stock, cutting means movably mounted on said stock, said cutting means being adapted when in drilling position to project outwardly beyond the periphery of the stock and being 10 also adapted to assume an inoperative position permitting the underreamer to pass through the casing of a well, and means movably mounted on said stock operating upon the withdrawal of the underreamer 15 from said casing to retain said cutting means in inoperative position, said last named means being adapted upon the entry of the underreamer in the casing to be actuated to thereby permit said cutting means 20 to assume a drilling position upon the issuance of the underreamer through the bottom of said casing.

3. An underreamer having a stock, cutting means movably mounted on said stock, 25 said cutting means being adapted when in drilling position to project outwardly beyond the periphery of said stock and being also adapted to assume an inoperative position permitting the underreamer to pass 30 through the casing of a well, and means mounted upon said stock adapted upon moving outwardly from the periphery of said stock to maintain said cutting means in inoperative position.

35. 4. An underreamer having a stock, a spring, cutting means yieldingly connected to said stock through said spring, said cutting means being adapted when in drilling position to project outwardly beyond the 40 periphery of said stock and also being adapted to assume an inoperative position permitting the underreamer to pass through the casing of a well, said spring being energized when said cutting means is in inoperative 45 position, and means mounted upon said stock operating upon the withdrawal of the underreamer from the casing for retaining said spring in energized condition.

5. An underreamer having a stock, cutting means movably mounted on said stock, 50 said cutting means when in drilling position being adapted to project outwardly beyond the periphery of said stock and also being adapted to assume an inoperative position permitting the underreamer to pass through the casing of a well, means movably mounted on said stock and adapted to move outwardly beyond the periphery thereof for maintaining said cutting means in inoperative 55 position, and means for preventing said last named means from executing an outward movement with respect to said stock when the underreamer issues through the bottom of the casing.

6. An underreamer having a stock, cutting

means movably mounted on said stock, said cutting means being adapted when in drilling position to project outwardly beyond the periphery of said stock and also being adapted to assume an inoperative position, permitting the underreamer to pass through the casing of a well, and spring actuated means for maintaining said cutting means in inoperative position, said spring actuated means having a constant tendency to assume a position for retaining said cutting means in inoperative position and automatically operating upon emergence from the top of the casing of a well to retain said cutting means in inoperative position.

7. An underreamer having a stock, a spring, cutting means yieldingly connected to said stock through said spring, said cutting means being adapted when in drilling position to project outwardly beyond the periphery of said stock and also being adapted to assume an inoperative position permitting the underreamer to pass through the casing of a well, a spring actuated latch mounted on said stock and adapted to move outwardly beyond the periphery thereof, said latch being adapted upon moving outwardly to retain said cutting means in inoperative position, and means movable by said spring for preventing outward movement of said latch upon the issuance of the underreamer through the bottom of the casing.

8. An underreamer having a stock, a spring, cutting means yieldingly connected to said stock through said spring, said cutting means being adapted when in drilling position to project outwardly beyond the periphery of the stock and also being adapted to assume an inoperative position permitting the underreamer to pass through the casing of a well, a plurality of latches pivotally mounted upon said stock, and springs operatively interposed between said stock and said latches and constantly tending to move said latches outwardly beyond the periphery of said stock, said latches when moved outwardly being adapted to maintain said cutting means in inoperative position.

9. An underreamer having a stock, a spring, cutting means yieldingly connected to said stock through said spring, said cutting means being adapted when in drilling position to project outwardly beyond the periphery of said stock and also being adapted to assume an inoperative position permitting the underreamer to pass through the casing of a well, said spring being adapted to be energized by the movement of said cutting means to inoperative position and being adapted to induce the return of said cutting means to drilling position, a plurality of oppositely disposed latches pivotally mounted upon said stock, said latches being adapted upon an outward movement beyond the periphery of said stock to assume a posi-

tion preventing said spring from returning said cutting means to drilling position, and a plurality of slides mounted upon said stock and actuated by said spring for preventing 5 said latches from moving outwardly when the underreamer issues from the bottom of the casing.

10. An underreamer having a stock, a spring, a rigid bit movably connected to 10 said stock through said spring, said bit having cutting portions which when the bit is in drilling position project outwardly beyond the stock on opposite sides thereof, and means for causing said bit to assume a position 15 permitting the underreamer to pass through the casing of a well, said means being operatively associated with said stock and bit members and including a pin and a slot having angularly disposed portions for 20 receiving said pin, said pin being carried by one of said members and said slot being formed in the other of said members.

11. An underreamer involving a stock and cutting means, together with spring means 25 for normally holding said cutting means in cutting position, said cutting means having integrally connected cutting portions adapted when in drilling position to project outwardly beyond the periphery of the stock 30 on opposite sides thereof and also adapted to assume an inoperative position permitting the underreamer to pass through the casing of a well, said means also including a straight transversely disposed cutting portion 35 lying within the periphery of said stock when the said cutting means is in drilling position.

12. An underreamer involving a stock and cutting means, together with means for 40 moving said cutting means to cutting position, said cutting means having integrally united cutting portions adapted when in drilling position to project outwardly beyond the periphery of said stock and also 45 adapted to assume an inoperative position permitting the underreamer to pass through the casing of a well, and said cutting means also having a cutting portion extending radially of said stock between the cutting 50 portions aforesaid within the periphery of said stock.

13. An underreamer involving a stock, a bit movably connected to said stock, and means for moving said bit to drilling position, said bit having cutting portions adapted when the bit is in drilling position to project outwardly beyond the periphery of said stock on opposite sides thereof and also 55 adapted to assume an inoperative position permitting the underreamer to pass through the casing of a well, said bit also having a cutting portion integrally united to the cutting portions aforesaid and extending radially of said stock when said bit is in drilling 60 position.

14. An underreamer involving a stock, a bit movably connected to said stock, and yielding means for moving said bit to drilling position, said bit having cutting portions adapted when the bit is in drilling position 70 to project outwardly beyond the periphery of said stock on opposite sides thereof and also adapted to assume an inoperative position to permit the underreamer to pass through the casing of a well, and said bit 75 also having a plurality of straight cutting edges sloping upwardly from the central portion of said bit toward the said cutting portions.

15. An underreamer bit having curved 80 cutting portions at its opposite ends, a straight cutting portion intermediate of and extending at an angle to said curved cutting portions and a bearing face upon its upper side, said portions first named being 85 adapted to project outwardly beyond the periphery of the stock of an underreamer, and said bearing face being adapted to engage an underreamer stock.

16. An underreamer bit formed with an 90 angular slot adapted to receive a member carried by an underreamer stock and having a centrally disposed cutting portion on its lower side and a bearing face on its upper side, the ends of said cutting portion 95 being adapted to project outwardly beyond the stock of an underreamer, and said bearing face being adapted to engage an underreamer stock.

17. An underreamer having a stock, a 100 spring, a rigid bit, and a rod movably connected to said bit and adapted to energize said spring, said bit being formed with an angular slot and having cutting portions adapted when in drilling position to project outwardly 105 beyond the periphery of said stock and also being adapted to assume an inoperative position permitting the underreamer to pass through the casing of a well, and said stock being provided with a pin extending into 110 said slot.

18. An underreamer having a stock provided at its lower end with bearing faces for resisting the upward thrust of a bit, a spring housed within said stock, a bit having bearing faces adapted to engage the said bearing faces of the stock, said bit having cutting portions which are adapted when in drilling position to project outwardly beyond the periphery of said stock and which are also 120 adapted to assume an inoperative position permitting the underreamer to pass through the casing of a well, a rod movably connected to said bit and adapted to energize said spring, and means for rotating said bit 125 while out of contact with said bearing faces of the stock to cause said bit to assume a position permitting the underreamer to pass through the well casing.

19. An underreamer having a stock, a 130

spring, a bit having cutting portions adapted when in drilling position to project outwardly beyond the periphery of said stock and also adapted to assume an inoperative position permitting the underreamer to pass through the casing of a well, a rod pivotally connected to said bit and adapted to energize said spring when said bit is caused to assume the position for passing through the well casing, and means for causing said bit to rotate upon said rod, said rod being capable of longitudinal movement only with respect to said stock.

20. An underreamer having a stock, a spring, a bit having cutting portions adapted when in drilling position to project outwardly beyond the periphery of said stock and also adapted to assume an inoperative position permitting the underreamer to pass through the casing of a well, a rod to which said bit is rotatably connected and which is adapted to energize said spring when said bit is caused to assume the position for passing through the well casing, and means for relieving said bit of the pressure of said spring during the rotation of said bit to its inoperative position.

21. An underreamer having a stock, a spring, integral cutting means yieldingly connected to said stock through said spring and having integral cutting portions adapted when in drilling position to project outwardly beyond the periphery of said stock and also adapted to assume an inoperative position permitting the underreamer to pass through the casing of a well, means operatively interposed between said spring and said cutting means for normally maintaining said cutting means in drilling position, and means for relieving said cutting means of the pressure of said spring during the movement of said cutting means to inoperative position.

22. An underreamer having a stock, a bit having cutting portions adapted when in drilling position to project outwardly beyond the periphery of said stock and also adapted to assume an inoperative position permitting the underreamer to pass through the casing of a well, means for operatively connecting said bit to said spring, and a plurality of means slidably mounted on said stock and adapted to actuate said connecting means to effect a compression of said spring, said last named means having portions adapted to extend outwardly beyond the periphery of said stock so as to be capable of contacting the lower end of the well casing and being also adapted to move inwardly toward the axis of said stock so as to pass through said well casing.

23. An underreamer having a stock, a spring, a bit having cutting portions adapted when in drilling position to project outwardly beyond the periphery of said stock

and also adapted to assume an inoperative position permitting the underreamer to pass through the casing of a well, a rod pivotally connected to said bit and adapted to energize said spring, a key movable with said rod and having its ends extending into slots formed in said stock, and a plurality of slides which engage and are adapted to actuate said key to cause said rod to energize said spring, said slides having members movably mounted thereon adapted to project outwardly beyond the periphery of said stock so as to extend beyond the interior of the said well casing.

24. An underreamer having a stock, a spring, a bit having cutting portions adapted when in drilling position to project outwardly beyond the periphery of said stock and also adapted to assume an inoperative position permitting the underreamer to pass through the casing of a well, a rod movably connected to said bit and adapted to energize said spring, means slidably mounted on said stock for actuating said rod to energize said spring, and means movably mounted on said stock for retaining said last named means in the position in which said spring is energized.

25. An underreamer having a stock formed with a spring receiving chamber, a spring within said chamber, a seat for said spring secured to said stock, a slotted rod extending through and adapted to compress said spring, a bit pivotally connected to the lower end of said rod, said bit having cutting portions adapted when in drilling position to project outwardly beyond the periphery of said stock and also adapted to assume an inoperative position permitting the underreamer to pass through the casing of a well, a key extending through the slot in said rod, slides connected to the opposite ends of said key and slidable longitudinally with respect to said stock, and a plurality of blocks movably mounted on the respective slides, said blocks being adapted to assume a position permitting the underreamer to pass through the casing of the well and being also adapted to project outwardly from the periphery of said stock beyond the interior diameter of the well casing.

26. An underreamer having a stock formed with an interior chamber extending longitudinally thereof, a spring within said chamber, a rod extending through and adapted to compress said spring, a bit pivotally connected to said rod, said bit having cutting portions adapted when in drilling position to project outwardly beyond the periphery of said stock and also adapted to assume an inoperative position permitting the underreamer to pass through the casing of a well, and means adapted to be actuated by the said well casing for causing said bit to assume a position permitting the under-

reamer to pass through the well casing, said rod being formed with an enlarged portion which cooperates with the walls of said chamber to guide said rod.

27. An underreamer having a stock, a spring, a bit having cutting portions adapted when in drilling position to project outwardly beyond the periphery of said stock and also adapted to assume an inoperative position permitting the underreamer to pass through the casing of a well, a rod pivotally connected to said bit and adapted to compress said spring, a plurality of slides mounted upon said stock and movable longitudinally thereof, means for operatively connecting said slides to said rod, a plurality of blocks movably mounted upon the respective slides, said blocks being adapted to assume a position permitting the underreamer to pass through the casing of a well and being adapted to project from the periphery of said stock beyond the interior diameter of the well casing and also being adapted to be actuated by said well casing to operate said slides, and a plurality of spring-pressed latches mounted upon said stock and respectively adapted to engage said slides to lock the latter in a position corresponding to the inoperative position of said bit.

28. An underreamer having a stock, a spring, a bit having cutting portions adapted when in drilling position to project out-

wardly beyond the periphery of said stock and also adapted to assume an inoperative position to permit the underreamer to pass through the casing of a well, a rod pivotally connected to said bit and adapted to compress said spring when said bit is caused to assume the position for passing through the well casing, a plurality of slides operatively connected to said rod and slideable longitudinally with respect to said stock, said slides being provided with means adapted to be engaged by said well casing to effect an operation of said slides, and a plurality of latches movably mounted upon said stock and respectively adapted to engage said slides to retain the latter in a position corresponding to the inoperative position of said bit, said latches being adapted to project outwardly beyond the periphery of said stock when the underreamer is withdrawn from the well casing, and said slides constituting means for retaining said latches in a retracted position corresponding to the drilling position of said bit.

29. A well drilling tool involving a bit having curved segmental cutting portions at its opposite ends and a rectilinear cutting portion intermediate of and extending radially with respect to said segmental cutting portions.

In testimony whereof I affix my signature.

ALFRED G. HEGGEM.
